JAMES C. DAWSON, OF WEBSTER GROVES, MISSOURI, ASSIGNOR TO ELMA N. DAWSON,
OF WEBSTER GROVES, MISSOURI

LOOSE LEAF BINDER MECHANISM

Application filed May 31, 1930. Serial No. 458,449.

The objects of the invention are to provide simple and cheap means for securing the heads of the binder post in the cooperating binder bar to prevent play between the heads of the posts and the bar.

These and other objects of the invention will become apparent from the specification and the appended drawings, in which

Fig. 1 is a perspective view illustrating the apparatus;

Fig. 2 is a detail top view of one end of the U-shaped binder bar;

Fig. 3 is a vertical longitudinal section through one end of the binder;

Fig. 4 shows a detail plan of an alternative form of screw head abutment; and

Fig. 5 is a section along the line 5—5 of Fig. 4.

The binder bar 10 supports the paper holding posts 11 and 12 which may be solid and bear a circumferential channel cut adjacent their outer ends or as is usual, the posts may be adjustable in length. In this case, they are provided with two axial bores into which the screws 13 and 14 are threaded.

The upper binder bar 15 is formed in a U-section, one side of which, 16, is provided with apertures 18, 18, through which the heads of the screws may pass, while the opposing side 17 forms a stop limiting further insertion of the screw.

The means for locking the binder consists of a locking bar 19. Rivets 21, 21, joining the two sides of the U-binder bar passing through elongated slots 22 in the locking bar maintain the bar permanently but slidably within the U.

Other slots also formed in the bar 19 bear a circular portion 23 which allows clearance for the screw head and a slot portion 24 equal in width to the diameter of the screw.

A detent 25 is bumped into the bar 19 which may spring into the aperture 26 provided in the inner side 16 of the binder bar. Accidental dislodgement of the lock is thus prevented.

The shank of the screw is necessarily smaller than the post, and the head of the screw must pass through the holes in the paper and is, preferably equal in diameter

to the post. The apertures 18, 18, must give clearance to the screw head. Consequently, the two bars now locked together would have a longitudinal play equal to the difference in diameter between the screw shank and the post. By providing a buttress closely surrounding the periphery of the head, a socket is formed which prevents the head from moving in any direction. The buttress forming the rim of the socket may be solid and formed into or affixed to the U-bar wall 17 in any suitable manner, or the rim may be discontinuous, in which case the socket may be easily formed by thrusting up the fingers spaced 120° apart. I prefer the latter expedient.

If now, the fingers are made equal to, or but slightly longer than the thickness of the screw head, they will also serve the function of spacers maintaining the locking bar so spaced in relation to the opposing side 17 that clearance for the screw head is always provided between the locking bar 19 and the wall. Consequently, when the post is inserted, the slot portion 24 of the lock will always pass under the screw head, engage the shank and lock the binder fast.

In Fig. 4, an alternative form of screw head abutment is shown which consists of a washer like member 28 welded or otherwise affixed to the inner face of the side 17. The hole 29 provided in the washer exceeds but slightly the diameter of the head of the screw and holds the screw from any displacement in the manner previously discussed.

What I claim, is therefore, is;

1. In a post type binder, a post having a stem portion, a reduced portion, and a head portion, a binder bar bearing a socket adapted to engage the periphery of the head portion, a locking bar slidably mounted on the binder bar bearing a slot adapted to clear the head portion of the post in one position and to engage the reduced portion of the post in the second position, said locking bar being maintained in spaced relation with respect to the binder bar by engagement with the outer end of the socket.

2. In a post type binder, a post having a stem portion, a reduced portion and a head

portion, a binder bar bearing a plurality of projections protruding from its face a distance substantially equal to the height of the head portion, and a locking bar slidably maintained against the projections and held in spaced relation from the binder bar by the projections.

3. In a post type binder, a post having a stem portion, a reduced portion, and a head portion a U-shaped binder bar having on one side a perforation adapted to clear the head portion, and having a plurality of fingers projecting inwardly from the other side and adapted to engage the periphery of the head portion, a locking bar within the U-section having a perforation adapted to clear the head portion, and a communicating slot adapted to engage the reduced portion, maintained in spaced relation with respect to the unperfornated side of the U-binder bar by the fingers projecting therefrom.

4. In a post binder, a post having a stem portion and a reduced extensible portion bearing a head, a U-shaped binder bar bearing on one side a perforation adapted to clear the head, a socket adapted to engage the periphery of the head projecting inwardly from the other side a distance at least equal to the height of the head, a locking bar within the U-section maintained against the end of the socket, and provided with a keyhole-shaped slot adapted to engage the head.

5. In a loose leaf binder, a binder bar, a post, a plurality of projections on the face of the bar adapted to engage the periphery of the post at its terminus, a reduced portion on the post at a point removed from said terminus a distance equal to the height of the projections, and a locking bar slidably maintained against the projections and adapted to engage the reduced portion of the post.

6. A loose leaf binder comprising in combination a binder bar bearing a plurality of paper-holding posts, a U-shaped binder bar having sockets comprising inwardly directed buttresses adapted to receive the heads of the posts and to prevent motion of the heads maintained therein, and means engaging a reduced portion on the posts, and maintained within the U-shaped section to lock the posts within the sockets.

In testimony whereof I affix my signature.
JAMES C. DAWSON.
